UNITED STATES PATENT OFFICE.

GEORGE SCHLEUSSELBURG, OF DETROIT, MICHIGAN.

VAPOR-GENERATING APPARATUS.

1,278,390.

Specification of Letters Patent. Patented Sept. 10, 1918.

Application filed August 10, 1917. Serial No. 185,478.

To all whom it may concern:

Be it known that I, GEORGE SCHLEUSSELBURG, a subject of the Emperor of Germany, residing at Detroit, in the county of Wayne and State of Michigan, have invented certain new and useful Improvements in Vapor-Generating Apparatus, of which the following is a specification, reference being had therein to the accompanying drawings.

10 The invention relates to an apparatus for converting liquid hydro-carbons, such as gasoline, kerosene and the like and alcohol into gas vapor that may be used in a gas range or other gas consuming device for 15 cooking, heating or lighting purposes.

The invention consists in the matters hereinafter set forth and more particularly pointed out in the appended claims.

10 The drawing is a view in vertical section 20 of a device that embodies features of the invention.

As herein shown in one preferred form, a suitably designed base 1, that may have an opening 2 adapted to be closed by a slide 25 door 3, is provided at the lower end or foot with air inlet openings 4. A lamp 5 or other heating device which is insertible through the door, and which has preferably a circular burner 6 that may be manually regulated 30 by a handle rod 7, is placed in the base.

An annular fuel tank 8 is disposed axially over the casing 1, preferably in telescopic engagement with a suitable flange at the upper end thereof. A vapor receiving tank 12 35 is supported above the bore of the annular reservoir 8 with which it is in communication by a pair of coils or worms 17 and 18 extending upwardly from the lower portion of the annular reservoir 8 in close proximity to the burner 6, and another pair of 40 pipes 13 which connect the upper portion of the reservoir preferably with the base of the tank 12 so that they may act to return any condensate to the fuel tank.

45 Thus the liquid contents of the annular chamber and of the worms is in such proximity to the heat of the burner that it is readily vaporized and collects in the vapor chamber 12, the latter having a relief valve 50 14 to guard against excess pressure and the heat being conserved around it by a suitable shield which in this instance takes the form of a conoidal chimney 11 suitably mounted on the reservoir by a slip joint.

55 A pair of delivery pipes 16 extend from the upper portion of the vapor chamber 12

downwardly through the bore of the annular tank 8 so that they lie in the path of the gases of combustion of the flame, and discharge into the lower end portion of a pressure tank 15 which is closely embraced by the coils 17 and 18. The entrance of these pipes is at an interval above the lower end portion of the tank 15 and a discharge pipe 24 leads from the upper part thereof down 60 through the annular bore of the fuel tank, and turns in close proximity to the flame of the burner 6 and extends outwardly through the casing 1.

As practical adjuncts to the device there 70 is a filling opening plug at 9 for supplying fuel to the tank 8, a pressure gage 23 for the tank 15 and a lighting opening closed by a cover 28 for igniting the burner 6.

As a result of this construction the con- 75 duction of the heat up the inner wall of the reservoir, baffled as it is by the double helices of the tank coils which are necessarily always filled to the same level as the tank itself, insures complete vaporization of the 80 fuel and its discharge into the gas chamber which is itself heated by the ascending gas current.

Any condensation which might possibly occur is returned to the fuel tank while the 85 vapor is delivered to the pressure chamber that is in closest proximity of any of the apparatus to the flame, thereby locally increasing the pressure and causing an ejection of the gas in a manner that insures its 90 efficient combustion wherever it may be delivered. The apparatus is readily dismounted for repair or replacement and the simplicity of its construction minimizes the cost 95 of production.

Obviously, changes in the details of construction may be made without departing from the spirit of the invention, and I do not care to limit myself to any particular form or arrangement of parts.

100 What I claim as new is:—

1. A vapor generating apparatus comprising heating means, a fuel tank forming a passage for the gases of combustion from the heating means, a vapor collecting tank 105 above the fuel tank in communication therewith by pipes forming baffles for the gases of combustion and by pipes affording return passages for condensates in the vapor tanks to the fuel tank, both pipes being disposed in coils within the passage formed by the fuel tank, a pressure tank disposed within 110

the coils of the baffle pipes directly above the heating means into which the vapor tank is arranged to discharge above the lower end thereof and a delivery pipe from the 5 pressure tank extending from the body thereof in close proximity to the heating means and without the apparatus.

2. A vapor generating apparatus comprising a casing, a heating means removably 10 mounted in the lower portion thereof, an annular fuel tank detachably mounted on the casing as a flue for the heating means, a vapor tank disposed axially above the fuel tank, worm pipes connecting the base of the 15 fuel tank with the vapor tank above the base thereof and forming baffles in the bore of the fuel tank, means for discharging condensates in the vapor tank into the upper portion of the fuel tank, a pressure tank 20 disposed within the baffle coils of the worm pipe with the lower portion thereof just above the heating means in communication with the upper portion of the vapor tank and a delivery pipe extending from the body 25 of the pressure tank in close proximity to the heating means through the bore of the fuel tank and without the casing just above the heating means.

3. A vapor generating apparatus comprising a casing, a heating device detachably 30 in the casing, an annular fuel reservoir detachably mounted on the upper end of the casing with the bore thereof forming a flue for the heating device, a vapor tank disposed axially above the fuel tank, worm 35 pipes connecting the lower portion of the fuel tank with the vapor tank and forming baffles in the bore of the fuel tank, a chimney detachably mounted as an envelop for the vapor tank pipes extending from the 40 upper portion of the vapor tank downwardly into the flue of the annular fuel tank, a pressure tank supported in the worm pipes of the fuel tank in communication with the lower end with the tank pipe, a 45 discharge pipe leading from the upper portion of the pressure tank through the flue and without the casing and means for indicating the condition of the contents of the fuel and the pressure tanks. 50

In testimony whereof I affix my signature in the presence of two witnesses.

GEORGE SCHLEUSSELBURG.
